UNITED STATES PATENT OFFICE

2,127,590

SOUND AND PROJECTION APPARATUS

Joseph Erwood, Chicago, Ill., assignor, by mesne assignments, to Electro-Acoustic Products Co., Fort Wayne, Ind., a corporation of Illinois

Application December 21, 1936, Serial No. 116,977

4 Claims. (Cl. 88—28)

This invention which relates to an apparatus for the projection of sound and images is concerned primarily with a portable cabinet in which the operating units are contained. The apparatus in its entirety is designed to be carried around and set up in various places, and, consequently, is small, light, and easily set up for operation. With these objects in mind, the present improvements are directed to a cabinet containing a sound apparatus, a picture projector, a screen on which images may be thrown, and means for framing and advancing a film through the projector so that successive images may be exhibited upon the screen. In the accomplishment of these purposes I have provided an apparatus which is inexpensive, simple to produce and use, and also convenient to carry around and stow away.

In the embodiment of this invention which is shown in the accompanying drawings, Figure 1 is a view in perspective of the cabinet;

Fig. 2 is a perspective view of the cabinet with one side wall dropped down and the lid partially opened, showing the parts in the interior of the cabinet as they are arranged for storage there-

within;

Fig. 3 is a view in perspective of the cabinet opened up with the several units arranged in operative position;

Fig. 4 is a perspective sectional view of the sound reproducer pick-up arm within its folding support;

Fig. 5 is a fragmentary detail on an enlarged scale of the mounting within the cabinet for the projector supporting arm;

Fig. 6 is an enlarged detail in section taken on line 6 of Fig. 3;

Fig. 7 is a vertical section through the forward end of the projector showing the film gate and feeding spool together with a slide film in operative position;

Fig. 8 is a detail in section on line 8—8 of Fig. 7;

Fig. 9 is a sectional view on line 9—9 of Fig. 8; and

Fig. 10 is a view similar to Fig. 9 showing the framing mechanism adjusted to another position.

The cabinet herein illustrated is in the general form of a suitcase C having one side wall (not shown), a narrow front wall 11, a second side wall 12 which is removable, and a rear wall 13. Over the top of the cabinet is fitted another wall in the form of a lid L with depending flanges providing an enclosure over the cabinet top wall 14. A handle 15 is secured to the lid, whereby the

entire cabinet may be lifted up and be conveniently carried about.

The lid, as shown, is connected at one end flange by a pair of hinges 20 to the front wall of the cabinet. When fully open the lid will have swung through 180° at which point its end flange to which the hinges are attached will abut the front wall 11 of the cabinet (see Fig. 3). In addition, the opposite end wall and one of the side flanges of the lid each carries a pair of plate-lugs 21 adapted to enter socketed fixtures 22 on the corresponding walls of the cabinet. Associated with each such fixture is a spring yoke 23 adapted to swing over the proximate lug whereby to secure the lid in closed position.

The side wall 12 is detachably secured to the cabinet bottom 25 as by a pair of leaves 26 secured to the wall adjacent its lower edge, each leaf being formed with a hook 27 adapted to engage a pin 28 which is supported between a pair of joints 29 carried by a plate which is affixed to the cabinet bottom. In this manner a hinged connection is provided permitting the side wall 12 to be swung downwardly to a horizontal position where it may then disengage from the pins. In its up position, as illustrated in Fig. 1, these hinged connections are inseparable.

Within a cabinet of this construction I provide a supporting partition 35 parallel to the side wall 12 but spaced therefrom to form therewith an enclosure for the accommodation of a turntable T and a projector P. As shown, the turntable is of a diameter which extends nearly the entire distance between the cabinet front and rear walls and upwardly through a recess to a point beyond its top wall 14 and into the space below the enclosing lid. The turntable is held in place upon a pair of clips 36 which are affixed to the partition 35. Formed in this partition is an opening 37 which may be covered with a screen or other foraminous sheet for the emission therethrough of sound which emanates from a loud speaker which is mounted upon the rear face of the partition. As part of the sound apparatus I employ a motor driven spindle 38 (see Fig. 2) projecting through the cabinet top in a position to receive thereon the turntable when mounted as shown in Fig. 3. A reproducer pick-up arm 39 of channel formation is swingably mounted upon a post 40 carried on the cabinet top and provided at its free end with the usual needle for tracking in the grooves of a record which may be positioned upon the turntable.

When the turntable is taken off for vertical positioning as shown in Fig. 2, one wall of the

pick-up arm adjacent its free end may then be supported within a spring clip 41 having a pivotal mounting 42 upon a bracket 43 which is affixed to the cabinet top. At the time the turntable is set up for rotation, the clip is swung down to the dotted line position shown in Fig. 4 so as to clear both the pick-up arm and the turntable.

The projector P comprises a lamp housing in whose forward wall 51 is supported a lens 52 in adjacent but spaced relation to a second lens 53 which is carried in a swinging film gate 54. Between the two lens a slide film F is adapted to be advanced so as to expose to light rays passing through the lens the images which are to be successively displayed upon the screen S. In the construction shown, this screen is carried upon the rear face of the side wall 12. Adjacent one edge of the side wall is a hook 55 (see Fig. 6) engageable with a pin 56 supported between aligned joints 57 which are extended from one end of a plate 58 that is affixed to the inner face of the end flange of the lid. By this construction the side wall 12 may be hooked onto the lid, when the latter is in inverted position (see Fig. 3) thereby 25 to be supported vertically for the reception upon the screen of images thrown from the projector. To assist in this support I have provided upon the exterior face of the side wall 12 (as viewed in Fig. 1) a socketed fixture 60 having an associated 30 spring yoke 61 adapted to receive and lock with one of the plate-lugs 21 which is carried on an end flange of the lid.

The partition wall 35 which carries a speaker upon its rear face may also be detached from the cabinet for mounting at a remote point (see the dot and dash line showing in Fig. 3), in which event it remains connected by an electrical conductor to suitable apparatus (not shown) in the cabinet. By this optional arrangement, the images may be thrown onto the screen when the latter is supported either upon the cabinet lid or at a more remote point.

Arranged transversely within the projector is a spool comprising a hub 65 to the opposite ends of which are affixed sprocket wheels 66 adapted to engage within the usual rows of perforations adjacent opposite edges of the film F. A brake in the form of a leaf spring 67 extends from one wall of the housing to engage with the proximate sprocket wheel.

For advancing and framing the film, the spool is fitted with a set screw 68 which, when advanced, bears tightly against a sleeve 69 on which the spool is mounted. The sleeve surrounds a shaft 70 which extends through bearings formed in opposite walls of the housing. One shaft end 71 which is reduced in diameter is threaded to receive a nut 72 bearing against a spring washer 73 which abuts the proximate sleeve end. Upon the opposite shaft end, exteriorly of the housing, is fitted the hub 75 of a driving wheel 76 having a circular flange 77 near its periphery; a ratchet disk 78; a thin washer 79 of fibre or other appropriate material; and a control disk 80—all in the order named. The control disk is slightly recessed upon its inner face to partly receive the washer, ratchet disk and circular flange, whereby this assembly of operating parts will occupy but a short space upon the shaft end.

The mounting of the control disk upon the shaft is fast, whereas that of the ratchet disk is loose. The sleeve is drivingly secured to the shaft as by a cross pin 85 whose ends lie within slots extending longitudinally of the sleeve adjacent one end thereof which abuts the ratchet disk to establish

a frictional driving connection therewith. At one point the circular flange upon the driving wheel is interrupted to accommodate a pawl 86 pivoted at 87 to present its acting end against the periphery of the ratchet disk which, as shown, is provided with four teeth spaced 90° apart. Secured to the pawl at 88 is one end of a flexible cord 89 which passes over the back of the pawl, then around an extended portion of the circular flange of the driving wheel, and thence to a point 10 convenient to an operator for manipulation. Each pull of the cord sufficient to rotate the driving wheel a quarter turn produces a like movement of the ratchet disk and, in consequence, the shaft, whereby the spool advances the film a distance 15 equal to one exposure. A stop whereby to limit oscillations of the driving wheel to a prescribed range is provided by a tongue 90 extended outwardly from one wall of the housing to lie within an arcuate slot 91 whose length may be just 20 slightly more than 90°. At the conclusion of each advance of the driving wheel, release of the pulling cord will permit a spring 92 to return the wheel to initial position.

To frame the film the control disk is manually 25 rotated in a direction counter to operating movements of the pawl drive. By such rotation of the control disk the shaft is turned against the friction imparted by its end against the ratchet disk in response to tension of the spring washer 73 at 30 the opposite shaft end. The net result of this operation is to readjust the position of the shaft (and film) relative to the ratchet disk.

The projector has a swivel mounting upon one end of an arm 100 at whose other end is affixed a 35 plate 101. Opposite edges of this plate are adapted to be fitted within offset facing flanges 102, one pair of which is mounted upon a block 103 within the cabinet. The projector may accordingly be fitted within the cabinet, in the manner 40 shown in Figs. 2 and 5, where it is supported by the sliding fit of the plate 101 between the offset flanges which furnish a mounting therefor. A similar mounting is provided upon the exterior of the cabinet in a plate 106 from which extends 45 a pair of facing offset flanges 107 adapted to overlie opposite edges of the same plate 101. Upon such an exterior mounting the arm may be readily fitted with the projector lying out beyond the proximate end of the cabinet in a position to 50 throw images upon the screen which, when mounted on the free end of the lid L, is situated beyond the opposite cabinet end a distance substantially equal to twice the cabinet length. It will be noted, therefore, that although the cabinet 55 is small, the operating parts may be accommodated completely therewithin, yet when removed therefrom, will furnish mountings exteriorly thereof such that the distance between the projector and screen is substantially twice the long- 60 est dimension of the cabinet.

I claim:

1. A projector apparatus comprising an elongated portable cabinet, a lid on said cabinet, hinge means on the lid and connected to one end of 65 the cabinet and adapted to carry the lid through 180° to an open position where its free end lies twice the cabinet length from its closed position, means for supporting the lid in such open position, a projector, means for mounting the projector in one position within the cabinet and in another position exteriorly thereof at a point adjacent the cabinet end opposite that whereon the lid is hinged, a screen and means for mounting the screen in one position within the cabinet and 75

in another position upon the lid adjacent its free end whereby to lie remote from the projector a distance substantially twice the long dimension of the cabinet.

- 5 2. A projector apparatus comprising an elongated portable cabinet having a removable side wall, a lid on said cabinet, hinge means on the lid and connected to one end of the cabinet whereby to swing the lid through 180° to an open position where its free end lies twice the cabinet length from its closed position, means for supporting the lid in such open position, a projector, means for mounting the projector in one position within the cabinet, and in another position 10 exteriorly thereof at a point adjacent the cabinet end opposite that whereon the lid is hinged, and means for mounting the cabinet side wall upon the lid end remote from the projector to serve as a screen therefor.
- 15 3. A projector apparatus comprising an elongated portable cabinet having a removable side wall, a lid on said cabinet, hinge means on the lid and connected to one end of the cabinet said lid having means to secure the removable side wall in place, the lid being adapted to swing through 180° to an open position where its free end lies twice the cabinet length from its closed position, means for supporting the removable

25 cabinet side wall upon the lid, when in open position, adjacent its free end, one face of the side wall being adapted to serve as a screen, a projector, means for mounting the projector in one position within the cabinet and in another position exteriorly thereon at a point adjacent the cabinet end opposite that whereon the lid is hinged whereby to throw images upon the screen.

4. A projector apparatus comprising a portable carrying case having a cover hinged along a top edge thereof and swingable outward to a horizontal position at one side of the carrying case, a picture projector mounting means upon said carrying case opposite the wall upon which said cover is hinged, a picture projecting lantern 15 adapted when mounted upon said mounting means to project a picture in the direction of said cover when said cover is in its fully opened position, a picture screen forming portion carried by said carrying case independently of said cover when the carrying case is closed, and means for securing said screen forming portion in a vertical position upon said cover at a distance from the projector greater than the largest dimension of said carrying case and in optical alignment 20 with said projector when said cover is fully opened and the apparatus is in operation.

JOSEPH ERWOOD.
